[57] CLAIM

The ornamental design for a package of peel off coupon for a security tracking system, as shown and described.

DESCRIPTION

FIG. 1 is a bottom plan view of package of peel-off coupons for a security tracking system showing my new design;

FIG. 2 is a front elevational view thereof;

FIG. 3 is an end elevational view thereof, with the opposite end being a mirror image;

FIG. 4 is a left side elevational view thereof, with the opposite side being a mirror image;

FIG. 5 is a sectional view taken along line 5—5 of FIG. 2;

FIG. 6 is a front elevational view of a second embodiment thereof, with the rear being flat an unornamented; and,

FIG. 7 is an enlarged left side elevational view thereof, with the right side being a mirror image of FIG. 3.
